Primary Examiner — Calvin E Vansant

Assistant Examiner — Benjamin L. Gray

CLAIM

The ornamental design for an electric wine opener, as shown and described.

DESCRIPTION

FIG. 1 is a perspective view of an electric wine opener showing the new design.

FIG. 2 is a partially enlarged perspective view thereof, illustrating the top portion of the electric wine opener in FIG. 1.

FIG. 3 is a front view of the electric wine opener of FIG. 1. FIG. 4 is a rear view of the electric wine opener of FIG. 1. FIG. 5 is a side view of the electric wine opener of FIG. 1. FIG. 6 is an opposite side view the electric wine opener of FIG. 1.

FIG. 7 is an enlarged top view the electric wine opener of FIG. 1; and,

FIG. 8 is an enlarged bottom view the electric wine opener of FIG. 1.

The evenly dashed lines in the figures illustrate portions of the electric wine opener that form no part of the claimed design. The dash-dot-dash lines in FIGS. 1 and 2 are for the purpose of illustrating the enlarged view indicators and form no part of the claimed design.

1 Claim, 8 Drawing Sheets
